FUEL BURNER CONTROL SYSTEM

Hubert T. Sparrow, Minneapolis, Minn., assignor
to Minneapolis-Honeywell Regulator Company,
Minneapolis, Minn., a corporation of Delaware

Application January 28, 1939, Serial No. 253,321

22 Claims. (Cl. 158—28)

This invention relates broadly to automatic control systems for fuel burners, and is directed more particularly to that type of system in which the room thermostat, or other control instrumentality, energizes a timer, such as a bimetallic element, which in turn operates the switch controlling the burner motor. In such systems the bimetallic timer takes a certain length of time to heat sufficiently to close the burner motor switch after the heater for the timer has been energized by the room thermostat, and a certain length of time to open the switch after the heater has been deenergized. Therefore if a power failure should occur stopping the burner motor, and then the power should return before the bimetallic timer had had sufficient time to open the burner motor switch, the burner motor would be immediately reenergized without the interposition of a time period sufficient to clear the furnace of combustible gases. Although such a system would probably operate satisfactorily, still a system which provides for a scavenger period each time the burner motor is shut down is preferred.

It is therefore an object of the present invention to provide a system of the above type having a means for providing a scavenger period whenever the burner is shut down.

A further object is to provide a system of this type in which the burner motor switch is opened independently of the timer whenever the heater for the timer is deenergized for any reason whatever and to prevent reclosing of the switch until the timer has cooled off sufficiently to return to its cold position.

A further object is to provide a magnetic interlock between a thermal timer and a switch operated thereby, the interlock being so designed that the switch will move to one of its positions independently of the timer whenever the heater for the timer is deenergized.

A still further object of the invention is to provide a system in which a timer, under the control of a room thermostat or other control instrument, operates a switching means which, in the cold position of the timer, closes the ignition circuit and holds the burner motor circuit and which, as the timer heats up, first closes the burner motor circuit and later opens the ignition circuit, means being provided also for returning the switching means to its original position independently of the timer whenever the burner motor is deenergized and for preventing its movement from this position until the timer has returned to its original position.

These and other objects will readily become apparent as the following specification is read in the light of the accompanying drawing, in which

Figure 1 is a diagrammatic illustration of one form of my invention employing intermittent ignition, and

Figure 2 is a diagrammatic illustration of a slightly modified form having a constant ignition.

The present application is drawn to the same basic system that has been disclosed in the applications of John M. Wilson Serial Nos. 253,337 and 253,338 and filed on Jan. 28, 1939, and the application of William J. McGoldrick Serial No. 253,309 filed Jan. 28, 1939.

15 Referring to Figure 1 of the drawing, a space thermostat is generally indicated at 11 and comprises a bimetallic element 12 which is fixed at one end and at its free end carries a switch arm 13 which, on a decrease in temperature, is adapted to engage a stationary contact 14. Although a thermostat of the bimetallic type has been disclosed, it will be understood that any other type of control instrumentality may be used, such as a bellows thermostat or a pressure responsive device.

20 Indicated generally at 15 is a safety switch which is composed of a pair of resilient contact blades 16 and 17 which are mounted at one end on the brackets 18 and 19, respectively. The blade 16 carries at its free end a contact 20 and the blade 17 carries at its free end a contact 21, these contacts being held in engagement under certain conditions which will be later described.

25 Mounted at one end on a bracket 24 is a thermal timer 25 in the form of a bimetallic element. At its free end the bimetallic element carries an insulating tip 26 and in the cold position of the timer 25 such as shown in Figure 1, the tip 26 engages underneath the spring blade 17 and holds the contacts 20 and 21 in engagement. Closely associated with the timer 25 is a heating element 27 which is adapted to heat the bimetallic timer 25 and cause it to flex toward the left, as seen in Figure 1. The upper end of the timer carries a contact 28 which in the cold position of the timer engages stationary contact 29. The upper end of the timer also carries contact 30 which under certain conditions cooperates with the contact 31 which is mounted on resilient blade 32 connected to the bracket 33.

30 A combustion switch is indicated generally at 35 and is composed of a switch arm 36 which cooperates with a stationary contact 37. This com-

bustion switch is of the type in which a temperature responsive element responds to the temperature of combustion, either in the furnace or in the stack, and operates the switch arm 36 by means of a slip friction connection so that the switch arm moves in response to changes in temperature rather than any definite temperature. In this particular switch, the switch arm 36 engages the stationary contact 37 on an increase in temperature and opens the circuit on a decrease in temperature.

Pivoted about a common pivot 40 is a pair of members 41 and 42. These members may be composed of some suitable magnetic material such as soft iron. It will be seen that the weight of the member 41 is all to the right of the pivot 40 as seen in Figure 1 so that if unconfined this member will rotate in a clockwise direction until it engages the stop 43. Wrapped around one leg of the member 41 is a coil 44 which when energized produces a magnetic pull causing the member 41 to attract the member 42 thereby preventing their separation. The member 42 is connected to the thermal timer 25 by means of the link 45. Pivoted at 46 is an arm 47 which carries at its lower end a mercury switch 48. The switch 48 carries at one end a pair of electrodes 49 and 50 and inserted into the other end of the switch and extending longitudinally of the switch for the major portion thereof is a second pair of electrodes 51 and 52. The arm 47 is connected to member 41 by means of the link 53 and with the member 41 engaging the stop 43, it will be seen that the switch 48 is tipped to a position where the mercury 54 closes the circuit between the electrodes 49 and 50 and opens the circuit between electrodes 51 and 52.

Insulatingly carried by the upper leg of the member 41 is a switch contact 55 mounted on the resilient blade 56 and the switch contact 57 carried by the resilient blade 58 is likewise insulatingly carried by the member 42, these switch blades being so positioned that they cause engagement of their contacts 55 and 57 only when the members 41 and 42 are substantially in engagement with each other.

Indicated at 60 is the usual burner motor for delivering fuel to the furnace and at 61 is an ignition device for igniting the fuel so delivered. The power for operating the control system is supplied by means of the supply lines 62 and 63.

Operation

As shown in Figure 1, the space thermostat 11 is satisfied and has been satisfied for a length of time sufficient to permit the thermal timer 25 to return to its cold position, at which time it moves the contact 28 into engagement with the stationary contact 29. The member 42 has been moved into engagement with the member 41 whose position is determined by the stop 43, and this movement has brought the contacts 55 and 57 into engagement with each other. The switch 48 is in a position where the electrodes 49 and 50 are bridged by the mercury and the circuit between the electrodes 51 and 52 is opened. The combustion switch having last responded to a decrease in temperature is in open position and the safety switch is in its normally closed position. The circuit to the heater 27 and the ignition device 61 is opened at the space thermostat and the circuit to the burner motor is opened at the electrodes 51 and 52 so that the system is completely deenergized and no power is being drawn from the supply lines 62 and 63.

On a decrease in temperature in the space due to the fact that the burner is shut down, the bimetallic element 12 will move the switch arm 13 into engagement with the stationary contact 14 and this action will set up the following circuit energizing the heater 27: supply line 62, conductor 65, bracket 18, switch blade 16, contacts 20 and 21, switch blade 17, bracket 19, conductors 66 and 67, bimetallic element 12, switch arm 13, contact 14, conductors 68, 69, and 70, heater 27, conductor 71, coil 44, conductors 72 and 73, switch blade 58, contacts 57 and 55, switch blade 56, and conductors 74 and 75 back to the other supply line 63. The ignition device is simultaneously energized through part of the above circuit from supply line 62, conductor 65, safety switch 15 as traced above, conductors 66 and 67, space thermostat 11, conductors 68 and 71, electrodes 49 and 50, conductor 78, ignition device 61, conductors 79 and 73, switch blade 58, contacts 57 and 55, switch blade 56, and conductors 74 and 75 back to the other supply line 63.

Thus when the space thermostat calls for heat, the heater 27 and the ignition device 61 are simultaneously energized so that a spark is supplied for igniting the fuel and the timing movement of the thermal timer 25 is initiated. It will be noted also that as the heater 27 is energized, the coil 44 which cooperates with the magnetic member 41 is also energized so that the two links 45 and 53 will be magnetically locked together by the members 41 and 42 rendering the thermal timer 25 operative to actuate the switch 48. As the thermal timer 25 starts to heat, it will flex toward the left as indicated in Figure 1 and will pull the switch arm 47 in a clockwise direction through the links 45 and 53 and the magnetic interlock 41 and 42. As the switch 48 is swung to the left, the mercury 54 will first bridge the electrodes 51 and 52 which will energize the burner motor 60 through the following circuit: supply line 62, conductor 65, safety switch 15, conductors 66 and 80, electrodes 52 and 51, conductor 81, burner motor 60, and conductors 82 and 75 back to the other supply line 63. The energization of the burner motor 60 while the ignition device is energized will normally produce combustion within the furnace and as a result of this combustion the combustion responsive switch arm 36 will engage the contact 37. As the thermal timer 25 continues to move to the left, the switch 48 will be tipped to a point where the mercury 54 will break the circuit between electrodes 49 and 50, thereby deenergizing the ignition device 61. Continued flexing of the thermal timer 25 will eventually bring the contact 30 into engagement with the contact 26 and if combustion has been established and the switch 36, 37 closed the following shunt circuit will be set up around the heater 27: from one side of the heater 27, conductor 70, conductor 85, switch arm 36, contact 37, conductor 86, bracket 33, switch blade 32, contact 31, contact 30, bimetallic element 25, and bracket 24 back to the other side of the heater 27. This shunt circuit will deenergize the heater 27 causing the thermal timer to cool and flex toward the right until it breaks the shunt circuit at the contacts 30 and 31. As soon as this shunt circuit is broken, the heater 27 is reenergized heating the timer and causing it to reclose the contacts 30 and 31. The thermal timer 25 will continue to make and break the contacts 30 and 31 in this manner as long as the system remains in this condition, and with

the thermal timer oscillating back and forth in this small range the coil 44 remains energized and the switch 48 remains in a position where the circuit between the electrodes 49 and 50 is broken and the circuit between the electrodes 50 and 52 is closed. This is the normal running condition of the system and at this time the burner motor will remain energized and the ignition device will remain deenergized.

As a result, the temperature in the space will begin to rise and when it has risen above the control point the bimetallic element 12 will move the switch arm 13 out of engagement with the stationary contact 14. This permanently breaks the circuit through the heater 27 and also through the coil 44 and as soon as this circuit is broken there is no more magnetic attraction between the members 41 and 42 and the member 41 will therefore be moved by gravity in a clockwise direction until it engages the stop 43, at which time it will have moved the switch 48 back to the position shown in Figure 1, when the burner motor circuit will be broken at the electrodes 51 and 52 and the mercury 54 will bridge the electrodes 49 and 50. This will not immediately reenergize the ignition device, however, because the circuit will be open at the switch arm 13 and contact 14. Immediately after the thermostat 12 has broken the circuit, the thermal timer 25 will still be hot and will be holding the member 42 toward the left as seen in Figure 1 so that the dropping out of the member 42 causes a separation of the contacts 55 and 57. It is now impossible to reclose the starting circuit even though the switch arm 13 should be moved into engagement with the contact 14 because this starting circuit must pass through the contacts 55 and 57. This is true of the circuit for the heater 27 and it is also true of the ignition device 61. The switch contacts 55 and 57 therefore prevent the burner motor 60 from being restarted after it has once been shut down until a predetermined time has elapsed, this time being the time necessary for the thermal timer 25 to cool sufficiently to return the member 42 to the position shown in Figure 1, at which time the contacts 55 and 57 are in engagement.

The above description of operation covers the normal starting and shut-down of the control system. Let it be assumed now that the space thermostat calls for heat and the starting circuits as set forth above have been established and the thermal timer 25 has flexed toward the left to close the burner motor circuit and subsequently open the ignition circuit. If for some reason, combustion does not take place, the switch arm 36 will not engage contact 37 so that when the contacts 30 and 31 are brought into engagement, the shunt circuit around the heater 27 will not be set up. The heater will therefore remain energized and the timer will continue to flex toward the left pressing back the contact blade 32, and eventually the tip 26 will pass from beneath the contact blade 17 permitting it to flex downwardly due to its bias. This will separate the contacts 20 and 21 which will shut off the electrical power to the entire system. The contact blade 17 engages the tip 21 in such a manner at this time that the switch will be locked in open position and in order to re-establish the supply of power to the system, the safety switch 15 must be manually reset. In order to accomplish this purpose, a manual reset member generally indicated at 90 has been provided. This reset member comprises a long leg 91 and a short leg 92

and a stem 93 which is provided with a reset button 94 and which is slidable in the stationary support 95. In order to reset the switch, the button 94 is pressed vertically upwardly which raises the legs 91 and 92 and the leg 91 raises the switch blade 16 out of the path of movement of the switch blade 17 and then the switch blade 17 is moved back to its latched position where it engages the upper side of the tip 26. It will be noted at this time that the switch contacts 20 and 21 still remain in open position, and if the thermal timer 25 has cooled sufficiently for the tip 26 to again move beneath the blade 17 then as the button 94 is released the blade 17 will be held in its raised position and the bias of the blade 16 will return the contact 20 into engagement with the contact 21. If the space thermostat is still calling for heat, the system will make another attempt at a normal start.

If the system is running normally and if flame failure occurs, the combustion responsive thermostat will move the switch arm 36 away from the contact 37 and the heater 27 will remain energized causing the thermal timer to continue to flex to the left until it trips the safety switch 15 to open position and locks itself out as described above.

If the switch arm 36 should become fused on the contact 37 so that these contacts will not separate when the system is shut down, it will be impossible to start the burner motor. The reason for this is that when the space thermostat closes the starting circuit at 13, 14, the heater 27 will be shunted by a circuit passing through the combustion switch 35, the conductor 86, bracket 33, switch blade 32, conductor 96, stationary contact 29, contact 28, bimetallic element 25, and bracket 24. This prevents the energization of the heater 27 and hence the thermal timer 25 will not be heated and will not close the circuit to the burner motor through the switch 48.

One of the main objects of the present invention is to provide a system which would move the burner motor switch to closed position immediately upon the failure of the power and which would prevent the reclosing of the switch until after a predetermined time interval had elapsed. The present system accomplishes this result due to the magnetic members 41 and 42 and the coil 44. Under normal operating conditions, the coil 44 is energized to lock the magnetic link between the links 45 and 53, but if the power should fail, even though the failure is only a momentary one, the coil 44 will be deenergized permitting the member 41 to drop back against the stop 43 and open the burner motor circuit at the switch 58. Even though the power is now immediately returned, the switch 48 will remain in the same position because the circuit to the coil 44 cannot be reclosed until the thermal timer 25 cools sufficiently to move the member 42 back to the position shown in Figure 1, at which time the contact 57 will be brought into engagement with the contact 55.

This system therefore provides for a minimum time interval during which the burner motor must remain deenergized after it has once been deenergized for any reason whatever. The time interval in each case is determined by the time necessary for the thermal timer to return to its cold position from its hot position.

Figure 2 discloses a slight modification of the invention disclosed in Figure 1. The space thermostat 11, safety switch 15, combustion

switch 35, as well as the burner motor 60 and ignition device 61, remain the same and will not again be described in detail. The magnetic members 41 and 42 are again pivoted on a common pivot 40 and again they carry the switch blades 56 and 58 with their associated contacts 55 and 57. In this case a coil 101 is wound around the member 41 and when this coil is energized, it acts as a primary winding of a transformer of which the high current winding 102 acts as the secondary. The thermal timer in this case is composed of a bimetal 103 which is of a type that is relatively highly resistant to the flow of electric current so that as current passes through the bimetal, heat is generated sufficient to cause the bimetal to flex toward the left in the manner produced by the heater 27 on the bimetal 25 in Figure 1.

As the space thermostat 11 calls for heat, a circuit is closed from the supply line 62, conductor 104, safety switch 15, conductors 105 and 106, bimetallic element 12, switch arm 13, stationary contact 14, conductors 107, 108, and 109, switch blade 58, contacts 57 and 55, switch blade 56, conductors 110 and 111, coil 101, and conductors 112, 113, and 114 back to the other supply line 63. This circuit energizes the coil 101 which induces a low voltage in the high current secondary winding 102. The high current is caused to flow in the following circuit: from one end of the coil 102 through conductor 115 to the upper end of the bimetallic element 103 through the bimetallic element, bracket 24, conductor 109, switch blade 58, contacts 57 and 55, switch blade 56, and conductor 110 back to the other side of the coil 102. The flow of current through the bimetallic element 103 causes it to heat due to its resistance properties and flex towards the left. As the energization of the coil 101 also produces a magnetic effect which tends to hold the members 41 and 42 together, the bimetallic element 102 will pull the link 53 and switch 120 with it as it flexes to the left. It will be noted that the switch 120 carries only two electrodes 121 and 122 which in the cold position of the bimetallic element 103 are open circuited, but as the element 103 flexes toward the left the switch 120 is tipped in a direction to cause the mercury 123 to bridge these electrodes. This closes a circuit from the supply line 62 through the conductor 104, safety switch 15, conductor 105, conductor 125, electrode 121, mercury 123, electrode 122, conductors 126 and 127, burner motor 60, and conductors 128, 113, and 114 back to the supply line 63. The ignition device 61 is connected in parallel across the burner motor 60 by means of conductors 129 and 130 so that in this modification the ignition device is energized at all times with the burner motor. The closure of the burner motor and ignition circuits normally establishes combustion and as a result the combustion switch 35 will move to closed position. As the bimetallic element continues to flex toward the left it will eventually bring the contact 30 into engagement with the contact 31 and at this time a shunt circuit will be set up around the bimetallic element 103 from the coil 102 so that no current will be flowing through the element and it will therefore begin to cool and flex toward the right. This circuit may be traced as follows: from one end of the coil 102 through conductor 115, contacts 30 and 31, contact blade 32, conductor 86, stationary contact 37, switch arm 36, conductor 85, conductors 108 and 109, switch blade 58, contacts 57 and 55, contact blade 56, and conductor

110 back to the other side of the coil 102. As the switch contacts 30 and 31 are opened due to the cooling of the bimetallic element 103 the shunt circuit is broken and the bimetallic element will again begin to heat causing it to flex to the left and reclose the contacts 30 and 31. This again closes the shunt circuit and bimetallic element 103 will continue to oscillate back and forth making and breaking the contacts 30 and 31 in the same manner as in the modification disclosed in Figure 1. At this time, of course, the switch 120 will be held in the position where it maintains the burner motor and ignition circuit closed and this is the normal running condition of the system.

When the space thermostat is satisfied, it moves the switch arm 13 out of contact with contact 14, which breaks the circuit to the coil 101 thereby releasing the member 41 for rotation in a clockwise direction by means of gravity to open the switch 120. Deenergization of the coil 101 also deenergizes the coil 102 and the timer 103 therefore starts to cool and as the member 41 separated the contacts 55 and 57 as it dropped out, the starting circuit cannot be reestablished until the timer 103 has returned to its cold position in which it moves contacts 55 and 57 into engagement again.

The system in Figure 2 will act in the same manner as the system in Figure 1 on failure to obtain ignition, failure of combustion after the system is in running condition and power failure. In each case after the burner motor is shut down, there is a minimum period during which it cannot be restarted and this period is determined by the time required for the timer 103 to move from its hot or normal running position to its cold position when it recloses the contacts 55 and 57. The system of Figure 2 is also provided with the conductor 96 and the contacts 29 and 28 prevent the system from being started in the event that the combustion switch contacts 36 and 37 have been stuck in their closed position. This result is obtained because the bimetallic element 103 is shunted by the following circuit: from one side of the coil 102, conductor 115, contacts 28 and 29, conductor 96, spring blade 32, conductor 86, stationary contact 37, switch arm 36, conductors 85, 108, and 109, switch blade 58, contacts 57 and 55, switch blade 56, and conductor 110 back to the other side of the coil 102.

It will be appreciated that the system of Figure 2 can be made into an intermittent ignition system in the same manner as the system of Figure 1. The systems are otherwise functional equivalents, the only difference between them being in the manner in which the timer is heated.

Various changes and modifications may occur to those who are skilled in the art and it is therefore to be understood that I am to be limited only by the scope of the appended claims and not by the embodiments disclosed.

I claim as my invention:

1. A fuel supply control system comprising in combination, fuel supplying means, a timer, a switch in control of said fuel supplying means, means connecting said timer and said switch whereby said switch is normally actuated by said timer, a condition responsive device for energizing said timer to cause it to move from a first position in which said switch is open to a second position in which said switch is closed, means responding to power failure for moving said switch to open position at any time independently of said timer, and means preventing the reclos-

ing of said switch until after said timer has returned to said first position.

2. A fuel supply control system comprising in combination, fuel supplying means, a timer, a switch in control of said means, means connecting said timer and said switch whereby said switch is normally actuated by said timer, a main switch, a condition responsive device for closing said main switch and energizing said timer to cause it to move from a first position in which said control switch is open to a second position in which said control switch is closed, means for returning said control switch to open position independently of said timer whenever said main switch is opened, and means preventing the reclosing of said control switch until said timer has returned to said first position.

3. A fuel supply control system comprising in combination, fuel supplying means, a timer, a switch in control of said means, means connecting said timer and said switch whereby said switch is normally actuated by said timer, electrical means for energizing said timer, a circuit for said energizing means, a condition responsive device for closing said circuit to energize said timer thereby causing it to move from a deenergized position in which said switch is open to a second position in which said switch is closed, means responsive at any time to power failure or the opening of said circuit by said condition responsive device for opening said switch independently of said timer, and means preventing the reclosing of said switch until after said timer has returned to said deenergized position.

4. A fuel supply control system comprising in combination, fuel supplying means, a timer movable from an initial position when energized and returning to said initial position when deenergized, a switch in control of said means, means for connecting said timer and said switch whereby the latter is operated by the former, a condition responsive device for energizing said timer on a demand for a change in said condition for causing said timer to move from said initial position in which said switch is open, to a range of movement in which said switch is held closed, and means responsive to power failure for breaking said connection and moving said switch to open position.

5. A fuel supply control system comprising in combination, fuel supplying means, a timer movable from an initial position when energized and returning to said initial position when deenergized, a switch in control of said means, means for connecting said timer and said switch whereby the latter is operated by the former, a condition responsive device for energizing said timer on a demand for a change in said condition for causing said timer to move from said initial position in which said switch is open, to a range of movement in which said switch is held closed, and means responsive to said condition responsive device after the demand for a change in said condition has been satisfied for breaking said connection and moving said switch to open position.

6. A fuel supply control system comprising in combination, fuel supplying means, a switch in control of said means, a timer, a connection between said timer and said switch comprising first and second members mounted for relative movement, said first member being connected to said switch and biased in a direction to open said switch, said second member being connected to said timer, electrical means for holding said

members against relative movement whereby said switch may be operated by said timer, an energizing means for said timer, a circuit for said energizing means, a condition responsive device for closing said circuit to cause said timer to move from a deenergized position in which said switch is open to a second position in which said switch is closed, power failure causing deenergization of said electrical holding means whereby said first member moves said switch to open position, and means preventing reenergization of said electrical holding means until said timer moves back to said deenergized position.

7. A fuel supply control system comprising in combination, fuel supplying means, a switch in control of said means, a timer, a connection between said timer and said switch comprising first and second members mounted for relative movement, said first member being connected to said switch and biased in a direction to open said switch, said second member being connected to said timer, electrical means which when energized holds said members against relative movement whereby said switch may be actuated by said timer, an operating means for said timer, energization of said operating means causing said timer to move from an initial position and deenergization of said operating means causing said timer to return to its initial position, and a condition responsive device for energizing said operating means and said electrical holding means for moving said timer from its initial position in which said switch is open to a second position in which said switch is closed, said condition responsive device deenergizing said operating means and said holding means upon being satisfied whereupon said first member immediately moves said switch to open position independently of said timer.

8. A fuel supply control system comprising in combination, fuel supplying means, a switch in control of said means, a timer, a connection between said timer and said switch comprising first and second members mounted for relative movement, said first member being connected to said switch and biased in a direction to open said switch, said second member being connected to said timer, electrical means which when energized holds said members against relative movement whereby said switch may be actuated by said timer, an operating means for said timer, a condition responsive device for energizing said operating means and said electrical holding means for moving said timer from a first position in which said switch is open to a second position in which said switch is closed, said condition responsive device deenergizing said operating means and said holding means upon being satisfied whereupon said first member immediately moves said switch to open position independently of said timer, and means to prevent the reenergization of said operating means and said holding means until said timer returns to said first position.

9. A fuel supply control system comprising in combination, fuel supplying means, a switch in control of said means, a timer, a connection between said timer and said switch comprising first and second members of magnetic material mounted for relative movement, said first member being connected to said switch and biased in a direction to open said switch, said second member being connected to said timer, electrical means for magnetizing one of said members whereby it attracts the other member and pre-

vents relative movement between them, an operating means for said timer, energization of said operating means causing said timer to move from an initial position and deenergization of said operating means causing said timer to return to said initial position, and a condition responsive device for simultaneously energizing said electrical means and said operating means for moving said timer from a first position in which said motor switch is open to a second position in which said switch is closed, deenergization of said electrical means by said condition responsive device or by power failure causing said first member to immediately move said switch to open position.

10. A fuel supply control system comprising in combination, a fuel supplying means, a switch in control of said means, a timer, a connection between said timer and said switch comprising first and second members of magnetic material mounted for relative movement, said first member being connected to said switch and biased in a direction to open said switch, said second member being connected to said timer, a first coil around one of said members for magnetizing it whereby it will attract the other member and prevent relative movement between them, means for energizing said timer including a second coil electromagnetically associated with said first coil, a circuit for said first coil, a condition responsive device for closing said last named circuit whereby said timer is caused to move from a first position in which said switch is open to a second position in which said switch is closed, said condition responsive device also acting to open said circuit and deenergize said coil whereupon said first member immediately opens said switch.

11. A fuel supply control system comprising in combination, fuel supplying means, a switch in control of said means, a timer, a connection between said timer and said switch comprising first and second members of magnetic material mounted for relative movement, said first member being connected to said switch and biased in a direction to open said switch, said second member being connected to said timer, a first coil around one of said members for magnetizing it whereby it will attract the other member and prevent relative movement between them, said timer comprising a thermal element of a material resisting the flow of electric current, a second coil electromagnetically associated with said first coil, a circuit including said thermal element and said second coil, and a condition responsive element for energizing said first coil which induces a current flow in said second coil causing said thermal element to heat and move from a first position in which said switch is open to a second position in which said switch is closed, deenergization of said first coil by said condition responsive device or by power failure causing said first member to move said switch to open position independently of said thermal element.

12. A fuel supply control system comprising in combination, fuel supplying means, a switch in control of said means, a timer, a connection between said timer and said switch comprising first and second members of magnetic material mounted for relative movement, said first member being connected to said switch and biased in a direction to open said switch, said second member being connected to said timer, a first coil around one of said members for magnetizing it whereby it will attract the other member and prevent relative movement between them, means

for energizing said timer including a second coil electromagnetically associated with said first coil, a circuit for said first coil, a condition responsive device for closing said last named circuit whereby said timer is caused to move from a first position in which said switch is open to a second position in which said switch is closed, said condition responsive device also acting to open said circuit and deenergize said coil whereupon said first member immediately opens said switch and a switch in series with said first coil, said last mentioned switch comprising a first contact carried by one of said members and a second contact carried by the other of said members, said contacts being closed only when said members are in juxtaposition whereby said first coil cannot be reenergized unless said thermal element is in said first position.

13. A fuel supply control system comprising in combination, fuel supplying means, a circuit therefor, an ignition device, a circuit therefor, switch means in said circuits, a timer, a connection between the timer and the switch means whereby the latter is operated by the former, means for energizing said timer, a circuit for said energizing means, a condition responsive device for closing said circuit to cause said timer to move from a first position, in which said switch means closes said ignition circuit and opens said fuel supplying means circuit, to a second position, said movement causing said switch means to first close said fuel supplying means circuit and later open said ignition circuit, means responsive at all times to power failure for immediately returning said switch means to its first position, and means preventing reenergization of said energizing means until said timer has returned to its first position.

14. A fuel supply control system comprising in combination, fuel supplying means, a circuit therefor, an ignition device, a circuit therefor, switch means in said circuits, a timer, a connection between the timer and the switch means whereby the latter is operated by the former, means for energizing said timer, a circuit for said energizing means, a condition responsive device for closing said circuit to cause said timer to move from a first position, in which said switch means closes said ignition circuit and opens said fuel supplying means circuit, to a second position, said movement causing said switch means to first close said fuel supplying means circuit and later open said ignition circuit, means responsive at all times to power failure or an opening of said circuit for said energizing means by said condition responsive device for immediately returning said switch means to its first position, and means preventing reenergization of said energizing means until said timer has returned to its first position.

15. A fuel supply control system comprising in combination, fuel supplying means, a circuit therefor, an ignition device, a circuit therefor, switch means for controlling said fuel supplying means and ignition circuits, a normally closed second switch in control of both circuits, a timer, a connection between said timer and said switch means whereby the latter is actuated by the former, an energizing means for said timer in series with said second switch, said timer having a deenergized position in which said switch means opens said fuel supplying means circuit and closes said ignition circuit, said timer having a second position in which it opens said second switch, a condition responsive device for closing the circuit to said energizing means to cause said timer to

move from said deenergized position toward said second position during which time said switch means first closes said fuel supplying means circuit and later opens said ignition circuit, means responsive to combustion for normally preventing said timer from moving into said second position but permitting such action if combustion does not take place, means responsive to the deenergization of the circuit to said energizing means for moving said switch means to its first position independently of said timer, and means preventing the reenergization of the circuit to said energizing means until said timer has returned to its first position.

16. In a device of the character described, in combination, a thermal timer, a control device having a plurality of control positions, means connecting the timer and control device, a heater for said thermal timer, a condition responsive device for energizing said heater to cause said thermal timer to move said control device from a first control position to another control position, and means responsive to the deenergization of said heater for moving said control device back to said first control position independently of said timer.

17. In a device of the character described, in combination, a thermal timer, a control device having a plurality of control positions, connections between said timer and said control device including an electromagnetic holding device, a heater for said thermal timer, a circuit including said heater and said electromagnetic holding device in series, a condition responsive device for closing said circuit causing said thermal timer to heat up and move said control device from a first control position to another control position, means for returning said control device to its first control position independently of said timer on deenergization of said circuit, and means preventing reclosing of said circuit until said thermal timer has returned to its cold position.

18. A fuel supply control system comprising in combination, a fuel supply control means, a timer, connections between said control means and timer, means for energizing said timer to cause it to move from a first position in which said fuel supply control means is inoperative to a second position in which said fuel supply control means is operative, said timer returning to its first position upon deenergization, and means for rendering said fuel supply control

means inoperative again independently of said timer whenever said timer is deenergized.

19. A fuel supply control system comprising in combination, fuel supplying means, a switch in control thereof, a timer, connections between said switch and timer, said timer, when energized, moving from a first position in which said switch is open, to a second position in which said switch is closed, and when deenergized returning to said first position, a main switch, a condition responsive device for closing said main switch and energizing said timer, and means for returning said control switch to open position regardless of the position of said timer.

20. A fuel supply control system comprising in combination, fuel supplying means, a timer, a switch in control of said means, means connecting said timer and said switch whereby said switch is normally actuated by said timer, electrical means for energizing said timer to move from a first position in which switch is open, to a second position in which said switch is closed, said timer returning to said first position upon deenergization, a circuit for said electrical energizing means, a condition responsive device for closing said circuit to energize said timer, and means responsive to power failure or the opening of said circuit by said condition responsive device for opening said switch regardless of the position of said timer.

21. A fuel supply control system comprising in combination, fuel supplying means, a timer having a deenergized position, means for energizing said timer, a switch in control of said fuel supplying means, connections by means of which said timer, when energized, closes said control switch, and means for opening said control switch independently of said timer substantially immediately whenever said timer is deenergized.

22. A fuel supply control system comprising in combination, fuel supplying means, a timer having a deenergized position, means for energizing said timer, a switch in control of said fuel supplying means, connections by means of which said timer, when energized, closes said control switch, means for opening said control switch independently of said timer substantially immediately whenever said timer is deenergized, and means preventing the reenergization of said timer until after it has returned to its deenergized position.

HUBERT T. SPARROW.
